CONDIMENT DISPENSER OR THE LIKE

Claes H. Peterson, Newton, Mass.

Application September 20, 1956, Serial No. 43,007

Term of patent 14 years

(Cl. D44—22)

Fig. 1.

Fig. 6.

Fig. 2.

Fig. 3.

Fig. 4.

Fig. 5.

Fig. 2 is a rear elevation of the dispenser;

Fig. 3 is a front elevation of the dispenser;

Fig. 4 is a side elevation of the dispenser;

Fig. 5 is a side elevation from the other side of the dispenser; and

Fig. 6 is a bottom view of the dispenser.

I claim:

The ornamental design for a condiment dispenser or the like, substantially as shown.
